BAND SPlicer

Albert T. Koehler, Herbert Palmleaf, and Melvin E. Ross, Chicago, Ill., assignors to A. J. Gerrard & Company, Melrose Park, Ill., a corporation of Illinois

Application May 28, 1956, Serial No. 587,564

15 Claims. (Cl. 81—9.1)

The invention relates generally to sealing mechanisms and more particularly to automatic seal attaching and crimping mechanisms adapted to be used therewith.

The present invention has among its objects the production of a seal attaching and crimping mechanism which may be automatic in operation to feed seals into the mechanism, and upon suitable actuation, crimp the seal about two strap ends. Thus where the novel mechanism is incorporated in a semi-automatic band splicing machine and the like, the operator may position two strap ends in operative relationship to the sealing jaws, and upon actuation of the mechanism, the band ends will be joined by a seal surrounding the same, the latter being crimped to provide an effective connection, following which the mechanism is recycled to position a fresh seal in operative position to receive the next pair of strap ends.

Another object of the invention is the production of such a mechanism which is so designed that it will take various sized strapping, both as to width and thickness, within reasonable limits, and effectively connect the same by a crimped seal, without requiring adjustment of the sealing mechanism, whereby a very efficient connection may be achieved providing up to approximately 88% strength and tension of the banding material.

Another object of the invention is the production of such a mechanism for splicing bands or the like, having very efficient safety devices whereby the machine may be set in operation only when the operator's hands are in a predetermined safe position before the machine can be actuated.

A further object of the invention is the production of such a mechanism which is comparatively simple, having a minimum of moving parts, which is very rugged and thus dependable in operation, requiring minimum amount of maintenance.

A further object of the invention is the production of novel indexing means whereby partially formed seals may be fed from a coil of strip material, to insure accurate positioning of the seal following its severance from the strip, novel means also being provided for automatically severing the seal during the operation of the machine.

A further object of the invention is the production of a novel seal which is so shaped that it may be readily partially fabricated in strip form and subsequently severed into individual seals, whereby the seal will be severed from the strip without producing dangerous sharp points or spiders which might result in injury to persons handling the banding, such result being achieved even though the severing means and seal indexing mechanism may be slightly out of adjustment, thus eliminating critical adjustments in the mechanism.

A further object of the invention is the production of such a mechanism which may be readily adapted to hydraulic actuation with accurate electrical control, resulting in a highly efficient, fast acting, relatively easily adjusted mechanism.

Many other objects and advantages of the construction herein shown and described will be obvious to those skilled in the art from the disclosure herein given.

To this end our invention consists in the novel construction, arrangement and combination of parts herein shown and described, and more particularly pointed out in the claims.

In the drawings, wherein like reference characters indicate like or corresponding parts:

10 Fig. 1 is a top plan view of a band splicing machine embodying the present invention, portions of the reel structure for holding a supply of seals in strip form, being omitted;

15 Fig. 2 is a side elevational view of the machine illustrated in Fig. 1;

Fig. 3 is a transverse sectional view taken approximately on line 3—3 of Fig. 1;

Fig. 4 is a sectional view taken approximately on the line 4—4 of Fig. 7;

20 Fig. 5 is a sectional view taken approximately on the line 5—5 of Fig. 3;

Fig. 6 is a sectional view taken approximately on the line 6—6 of Fig. 7;

25 Fig. 7 is a sectional view taken approximately on the line 7—7 of Fig. 6;

Fig. 8 is a sectional view taken approximately on the line 8—8 of Fig. 7, illustrating the sealing mechanism at the end of the crimping operation;

30 Fig. 9 is a top plan view of a portion of the seal guiding structure taken approximately on the line 9—9 of Fig. 5, with the cover member therefor removed to show the details of the seal advancing and indexing mechanism;

35 Fig. 10 is an elevational view looking from right to left as seen in Fig. 4, of the electrical control switch arrangement and actuating mechanism therefor;

Fig. 11 is a perspective view of a portion of a strip of connected seals adapted to be used with the present invention;

40 Fig. 12 is a perspective view of two strap ends joined together by means of a crimped seal as performed by the present invention; and

Fig. 13 is a diagrammatic figure of the electrical control circuits, which may be utilized in the machine illustrated.

45 While the novel seal attaching and crimping means illustrated in the drawings may have considerable application in various types of automatic sealing mechanisms, for the purposes of explanation, the mechanism is illustrated in conjunction with a novel machine designed to splice sections of banding, as for example, where strap material is to be reused, and short sections of the banding are therefore spliced into longer, reusable lengths. Thus in the machine illustrated the seals are adapted to

50 be automatically fed from a roll of seals into the crimping and attaching mechanism, and automatically positioned for engagement with a pair of strap ends, which may be manually positioned in operative relationship, following which the seal is crimped upon the band ends to securely attach the same together and the machine recycled automatically to bring a following seal into operative position for engagement with the next pair of strap ends to be joined.

55 The embodiment of the invention illustrated is adapted to be hydraulically actuated, a hydraulic pump driven by an electric motor, and controlled through electrically actuated valve structure, may be employed with the crimping mechanism to provide extremely dependable fast, positive action which may be accurately controlled by the electrical means.

60 Referring to the drawings, and particularly Figs. 1 and 2, the reference numeral 1 indicates generally a cabinet

type bench having a top 2 on which is positioned a plate 3, which for the purposes of reference will be termed a mounting or base plate, secured to the top 2 by suitable means such as bolts 4. In the embodiment of the invention illustrated the mounting plate 3 is adapted to carry all of the sealing and crimping mechanism indicated generally by the numeral 5, as well as the means for guiding the seals in strip form, into the sealing mechanism, and in addition thereto is adapted to supporting guiding means for the bands to be joined and the manually actuatable control mechanism.

In the construction illustrated, the guiding means for the bands to be joined comprises a pair of vertically extending standards 6 and 7, while the manual control mechanism includes a pair of switch actuating members comprising a lever 8 and a switch button 9. The seals are adapted to be supplied in a continuous roll which may be supported at the end of the machine adjacent the inlet for the seals by suitable supporting structure indicated generally by the numeral 11, only a portion of the latter being illustrated in Figs. 1 and 2, and including a seal guide member 12 illustrated as being of more or less arcuate shape.

The embodiment of the invention illustrated may be hydraulically actuated by a hydraulic cylinder, indicated generally by the numeral 13, adapted to receive suitable oil under pressure to reciprocate a piston and piston rod within the cylinder. The oil may be supplied from a tank or reservoir 14 by means of a hydraulic pump 15 driven by an electric motor 16, the oil being controlled with respect to the cylinder 13 by a suitable electro-magnetic valve structure 17, the various components being operatively connected by hoses indicated generally by the numeral 18.

The arrangement is such that, during operation, a seal which has previously been severed from the supply roll will be positioned at the top of the sealing mechanism 5, where a pair of strap ends may be positioned on the seal and by simultaneous actuation of the lever 8 and switch button 9, the seal will be folded around the strap ends and crimped thereon to securely join the latter, following which the jaws of the crimping mechanism will open to permit removal of the joined straps therefrom and the machine will complete a recycling operation to advance a successive seal into the sealing mechanism, sever the seal from the supply roll, and position the seal for engagement with a subsequent pair of strap ends, whereby the entire operation may be repeated.

In actual practice the operator normally would have a supply of pieces of strapping so positioned on the top 2 or other supporting structure that he may readily grasp one strap in his right hand and the second strap in his left hand, the adjacent ends of the straps extending in opposed relation between the operator's hands. He may then place the adjacent strap ends in proper relationship on the seal, which will bring his left hand directly above the switch lever 8, and his right hand directly above the switch button 9, so that when the strap ends are in proper position he may readily apply pressure to the lever 8 and the cap 9. Simultaneous actuation of these elements will result in the actuation of the crimping mechanism, folding the seal over on the strap ends, crimping the seal to join the ends and thereupon opening the jaws to permit the operator to remove the joined straps and place them to one side. Following opening of the crimping jaws, the mechanism will automatically recycle, feeding a new seal into the crimping mechanism, severing the seal from the supply roll, and bringing the severed seal into position for engagement with the next pair of straps. During this operation the operator may pick up the next pair of straps and position the ends thereof upon the seal which has been brought into operative position in the interim.

The present invention thus enables an inexperienced operator to perform splices very rapidly and six hundred splices per hour may be readily achieved.

The sealer mechanism

Referring to Figs. 3 through 8, the sealer mechanism 5 may comprise a pair of spaced substantially parallel side plates 21a and 21b, which extend through a more or less rectangularly shaped opening 22 in the plate 3 and may be supported by the latter by mounting bars 23 which may be secured to the plates 21a and 21b by screws 24, the bars in turn being secured to the plate 3 by suitable cap screws 25. As illustrated in Figs. 4 and 6, each of the side plates may be provided with a pair of vertically extending parallel slots 26, the slots 26 in the side plate 21a being connected by a transversely extending slot 27, the latter being positioned intermediate the ends of the respective slots 26, whereby the combined shape of the slots 26 and 27 is in the form of a letter H. The slots 26 may be closed adjacent the outer faces of the plates 21a and 21b by plates 28a and 28b, the latter plates being secured to the side plates 21a and 21b, respectively, by screws 29 adjacent the upper edge of the plates 28a and 28b and at their lower portions by the bar 23 and cap screws 24.

Extending between the side plates 21a and 21b are a pair of pins 31 having their ends disposed in corresponding slots 26 as clearly illustrated in Fig. 7, the plates 28a and 28b forming retaining members to prevent axial movement of the pins 31. Pivotedly mounted on each pin 31 is a plurality of crimping jaws 32, the particular construction illustrated utilizing three such jaws on each of the pins 31, and disposed intermediate the jaws are punch blocks 33, which as illustrated in Fig. 8, are generally rectangular in shape and provided at their upper edge with a recess or notch 34 therein, having a horizontal portion 35 which terminates in inclined faces 36. Positioned adjacent each of the side plates 21a and 21b are generally rectangular plate-like members 37 and 38, which for the purpose of identification will be respectively termed the lower cutter block or bar and the seal stop plate. Both of these plates may be provided with generally vertically extending slots 39 therein through which the pins 31 extend; whereby the plates 37 and 38 may move vertically with respect to the pins thus operating the jaws 32. Suitable spacers 40 are disposed between the plates 37 and 38 and the respective jaws 32 adjacent thereto.

As illustrated in Fig. 6, the plate 37 may be provided with a notch 41 in its upper edge, forming a shearing edge 42, the opposite edge portion of the plate 37 being relieved as indicated at 43, while the member 38 may be provided with a flat upper edge without a similar notch, as will be apparent from a reference to Fig. 6.

Each of the jaws 32 may be provided with a bore 44 therein in which are positioned pins, 45, the latter also extending through pairs of actuating links 46, each of which are positioned between a respective pair of jaws 32, and thus positioned below the punch blocks 33, as will be clearly apparent from a reference to Fig. 8. Also carried by each of the pins 45 adjacent the side plates 21a and 21b are cylindrically shaped rollers 48 which may cooperate with vertically extending guide rails 60 49 having inclined top faces 50, positioned adjacent the vertical edges of the side plates 21a and 21b and secured thereto by suitable means such as cap screws 51. As illustrated in Fig. 8, the free ends of the links 46 may be pivotally connected to a clevis block 52 rigidly mounted on the free end of the piston rod 53 of the hydraulic cylinder 13, the upper end block 54 of the cylinder being secured to the side plates 21a and 21b by bolts or screws 55 passing through the side plates and threaded into the block 54.

As will be apparent from a reference to Fig. 3, the clevis block 52 is provided with slots 56 therein, each adapted to receive the free end of one of the links 46, the pins 57 extending through the links 46 and cooperable bores in the block 52, axial movement of each pin 75 57 being restricted by the side plates 21a and 21b.

Carried by the side plate 21a and cooperable with the lower cutter bar 37 is an upper cutter block 58, portions of which are visible in Figs. 3, 4 and 8, the block 58 being generally L-shaped, having a vertically extending portion 59 and a horizontally extending portion 61 which, as illustrated in Fig. 3, is positioned in the cross slot 27 in the side plate 21a, the end face 62 of the portion 61 being positioned substantially in the plane of the inner face of the side plate 21a and cooperable with the cutting edge 42 of the lower cutter 37. It will be noted that the upper cutter block 58 is spaced from the bottom edge of the slot 27 to provide a passageway 63 therebelow for the seals, as will hereinafter be described.

General operation of the crimping mechanism

It will be appreciated from a study of Figs. 4, 6 and 8 that the crimping assembly comprising the jaws 32, punch blocks 33, spacers 49, seal stop plate 38 and upper cutter block 37, together with the pins 31, links 46, pins 47 and rollers 48, may be reciprocated in a vertical direction under the action of the piston rod 53. During such movement the pins 31 are restricted by the slots 26 in the side plates from moving other than in a vertical direction as defined by the slots. However, as the pins 45 are not confined by the side plates 21a and 21b, other than as to axial movement, the positioning and movement of the pins 45 may be controlled by the rollers 48 and guide rails 49, whereby the movement of the pins 45 is restricted to a vertical movement when the rollers 48 are disposed along the inner vertical edges of the guide rails 49, but as the rollers reach the upper end of each guide rail they may move laterally outward above the upper end face of each guide rail, permitting the jaws 32 to rotate about the pins 31 which at such point have approached the end of their travel in the slots 26 and are adapted to be seated on the upper end walls of the latter.

Thus assuming that the piston of the cylinder 13, and the piston rod 53 associated therewith, are at the end of their retractive movement, the crimping mechanism will substantially assume the relationships illustrated in Fig. 4, wherein the rollers 48 are disposed between the guide rails 49, the jaws 32 being rotated into an open position and the entire crimping assembly being withdrawn downwardly between the side plates 21a and 21b. As the rollers 48 reach the upper end faces of the guide rails 49 the links 46 will urge the pins 45 laterally outward to rotate the jaws into a closed position similar to that illustrated in Fig. 8. Upon return movement of the piston rod 53, the inclined top faces 59 of the guide rails 49 will urge the rollers 48 inwardly, whereupon the latter will be free to move downwardly as illustrated in Fig. 4.

Seal feeding mechanism

As illustrated in Figs. 3, 4, 9, 11 and 12, the seal indicated generally by the numeral 64, is formed from suitable metal stock, as for example, strip material, and is provided with a base portion 65 having a pair of side walls or flanges 66 adapted to be folded over as illustrated in Fig. 12 to form a generally tubular structure in which the strap ends S and S' may be positioned, the seal being partially severed as indicated at 67 and deformed out of the plane of the remaining portions of the seal to form an interlock between the seal and the strap ends, such interlocking structure being generally old in the art. As illustrated in Fig. 11, the seals 64 are adapted to be fabricated in a continuous strip of connected seals, the latter being joined together at opposite ends of the respective base portions 65 as indicated by dotted lines 67 in Fig. 11. It will be noted that the strip forming the seals is notched as indicated at 68 on the lines of juncture 67 of adjoining seals, forming a connecting web portion 69 at which the individual seals are to be subsequently severed. As illustrated, the end

edges of the side walls or flaps 66 of each seal may extend in the same direction as the lines of juncture 67, and the end edges may terminate in diagonally extending edge portions 71.

5 The construction of the seal is such that the web portion 69 is sufficiently long in the longitudinal direction of the strap, that the severing of the leading seal from the remainder of the strip will always occur at the web 69 and thus insure a sheared edge that is free from burrs or spiders, as they are called, which might cause injury to persons handling the strap. It will be appreciated that in the event the shearing of the leading seal took place at a point where a portion of the side walls or flanges 66 were likewise sheared, the projecting cutting of such side walls would form a sharp pointed burr or the like which could readily cause injury to persons handling the strap and if the notch 68 was more or less V-shaped, with the apex terminating on the shearing line 67, the severance would have to take place exactly at the apex or such a burr or spider would be produced, necessitating extremely accurate and critical adjustment of the feeding mechanism to insure cutting exactly between the seals. However, by utilizing a notched arrangement such as that illustrated, the web 69 may be of definite length, as for example three-sixteenths of an inch, enabling the shearing action to take place anywhere along the web and at the same time produce a uniform sheared edge on the seal free of burrs, etc.

Long strips of connected seals, such as that illustrated 30 in Fig. 11, may be arranged in coiled form and supported by a suitable supporting structure, indicated in general by the numeral 11 in Figs. 1 and 2, only a portion of such structure being illustrated, whereby the leading end of the strip may be fed upwardly on the curved ramp 12 to the seal advancing mechanism.

Referring particularly to Figs. 3 and 5, mounted on the base plate 3 is a pair of laterally spaced substantially parallel seal guide rails or bars 72, forming a passageway 73 therebetween adapted to receive the strip of seals as clearly illustrated in Figs. 3, 5 and 9. The rails 72 may be secured to the plate 3 by suitable means, as for example, shouldered cap screws 74 (see Fig. 1), four such screws being employed in the embodiment illustrated in the drawings, with such screws also being adapted to retain a cover plate 75 which is provided with a pair of longitudinally extending slots 76 adjacent the crimping mechanism 5 and a pair of key hole shaped openings 77 adjacent the guide 12 for engagement with the screws 74. Thus the cover 75 may be removed from the rails when desired, by sliding the cover to the left as viewed in Fig. 1 to permit the disengagement of the right hand end of the cover from the adjacent screws 74, which will simultaneously position the heads of the opposite pairs of screws 74 in the enlarged portion of the key hole slots 77, permitting the adjacent end of the cover plate to be raised upwardly, with the heads of the screws passing through the openings 77. The cover plate 75 may be locked in assembled relation on the guide rails 72 by suitable means, as for example, a bar lever 78 pivoted at 79 on a standard or column 81 mounted on the plate 3, the lever 78 being adapted to engage a locking stud 82 carried by the cover plate 75, thereby preventing movement of the plate in a releasing direction when the lever 78 is in the position illustrated in Figs. 1 and 2, but upon rotation of the lever upwardly to release the stud 82, the cover may be removed as described. A stud 83 on the plate 3 is adapted to engage the opposite side of the lever 78 to guide the latter into locking engagement with the stud 82.

It will be noted from a reference to Figs. 4 and 5, which show the cross sectional shape of the partially formed seal as it advances between the guide rails 72, that the side walls 66 of the seal diverge outwardly and upwardly from their junction with the base 65, and disposed in the passageway 73 between the guide rails 72

and secured to the cover plate 75 by suitable means such as screws 74', is an inner guide rail 72' which cooperates with the base plate 3, rails 72 and cover 75 to form a more or less C-shaped passageway for the strip of seals adjacent the crimping mechanism 5.

Referring to Figs. 3, 5 and 8, the means for advancing the strip of seals may include a rock lever 84 carried by a shaft 85 supported by a pair of spaced brackets 86, which in turn may be carried by the plate 3, the brackets having flanges 87 thereon adapted to receive studs 88 on which may be threaded nuts 89 for retaining the brackets in position. To add rigidity to the structure the brackets 86 may also be operatively connected to the plate 21a as hereinafter described, by a pair of studs 91 rigidly connected to the vertically extending flanges 92 of each bracket by lock nuts 93 threaded on the studs 91.

Carried by the lever 84 at the upper end which extends into an opening in the plate 3 thereof is a seal engaging pawl 94 which may be pivotally supported on a pin 95 carried by the lever 84, the pawl being biased 20 in a counterclockwise direction about the pin 95, as viewed in Fig. 3, by a torsion spring 96 having one end bearing on the intermediate web 97 of the lever and the opposite end on the pawl. As illustrated in Figs. 3 and 5, the pawl 94 may be provided with an upwardly extending portion 97, of generally triangular shape in cross section, having a pair of spaced ears or lugs 98 thereon adapted to enter the slots 68 of the strip of seals, as clearly illustrated in Figs. 3 and 5, whereby rocking movement of the lever 84 about the axis of the shaft 85 will result in reciprocation of the pawl 94.

Thus advancement of the strip of seals will take place when the lever 84 is rotated in a clockwise direction, whereas the lugs 98 of the pawl may move out of engagement with the slots 68 of the strip of seals, in opposition to the biasing spring 96, so that no movement of the strip of seals will be effected upon the return movement of the lever 84.

Suitable indexing means for the strip of seals may also be provided, that illustrated in the embodiment of the invention shown, comprising a pair of index pins 99 reciprocably mounted in bores 101 located in the respective guide rails 72 and having threaded stems 102 extending through apertures in the bottom wall of the bores 101, the pins 99 being urged inwardly by compression springs 103, each having one end seated on the head of the pin 99 and the opposite end on the bottom wall of the bore 101, as clearly illustrated in Fig. 5, with inward movement of the pins being restricted by lock nuts 104 on the threaded external ends of the respective pins, the lock nuts also providing a means of adjustment for the indexing structure. As illustrated in Fig. 9, the heads of the pins 99 may be provided with tapered or conical shaped edges 99' which are adapted to engage the inclined edges 71 of adjacent seals, operative to accurately position or index the seal with respect to the mechanism 5. The indexing means also is operative to insure retention of the advanced strip in position, while the feeder pawl 94 returns to its original position following advancement of the strip.

The seal advancing mechanism is adapted to be actuated by movement of the rod 53, with the details of such mechanism being illustrated in Figs. 3 and 8, and including a pair of axially movable shafts 105 supported in bushings 106 carried by the plates 21a and 21b. Connecting the ends of the shafts 105 adjacent the plate 21a is a cross bar 107 adapted to be rigidly connected to the shafts by threaded end portions 108 on the latter passing through the bar and secured by nuts 109, the cross bar being seated on shoulders defining the juncture of the threaded portion 108 with the body of the shaft.

Positioned at the opposite end of each shaft is a compression spring 111 bearing at one end on the adjacent bushing 106 and adapted to be compressed by lock nuts 112, the latter providing means for adjusting the degree

of compression of the springs 111, which are operative to bias the shafts 105 and cross bar 107 in a right-hand direction as viewed in Fig. 3.

The cross bar 107 may be connected to the lever 84 by suitable means, as for example a stud 113 having one end threaded into the bar 107 intermediate the shafts 105 and locked in place by a nut 114. The opposite end of the stud 113 is adapted to extend through a trunnion block 115 pivotally carried by the lever 84, the latter having a bifurcation 116 at the opposite side of the pin 33, between which bifurcation the block 115 may be pivotally supported by opposed bolts 117, threaded through the bifurcated portions 116. Adjustment of the trunnion block 115 along the stud 113 may be effected by adjustment of two pairs of lock nuts 118. Rigidly mounted on the shafts 105 are cam blocks 119, the latter being generally rectangular in shape and having an inclined upper or top face 121 engageable with rollers 122 mounted on bushings 123 supported on a pin 124 which also passes through the block 52 and piston rod 53, pinning the two together, and provided with threaded end portions 125 and 126, respectively, the end 125 being provided with a washer 127 and nut 128 adapted to retain the bushing 123 thereon and in like manner the bushing 123 on its end 126 may be retained by a nut 129.

It will be apparent that with this construction, as the piston rod 53 and structure carried thereby, including the pin 124 and rollers 122 carried thereby, approaches the end of its retracting movement, the rollers 122 will engage the inclined cam faces 121 of the blocks 119, urging the latter laterally and with its shafts 105 and cross bar 107, in opposition to the springs 111, axial movement of the shafts 105 resulting in movement of the trunnion block 115 thereby rocking the lever 84 about the axis of the shaft 85 to move the pawl 94 in a feeding direction toward the right as viewed in Fig. 3. The mechanism will normally be so adjusted that the lever 84 and pawl 94 will move the seals the desired amount to bring the junction of adjacent seals into engagement with the index pins 99 as illustrated in the drawings. The pins 99 are so positioned with respect to the face 62 of the upper cutter block 58 that the desired point of severance of the leading seal will be positioned in line with the face 62, and as the assembly carrying the lower cutter blade 37 moves upwardly, the cutters will shear the metal at the web 69 to sever the leading seal from the strip.

The control mechanism

As previously mentioned, the hydraulic valve structure indicated generally by the numeral 17 in the drawings, is adapted to be electro-magnetically actuated whereby the manually actuated controlling means may be in the form of electric switches. Likewise the reciprocation of the hydraulic piston and piston rod 53 may be accomplished by limit switches operated by the movement of the piston rod.

Referring to Figs. 3, 4, 8 and 10, carried by the plates 21a and 21b is a switch panel or plate 131 which may be secured to the plates 21a and 21b by respective bars 132, the latter being secured to the plates 21a and 21b by screws 133 and the panel 131 in turn, being secured to the bars by screws 134. The adjacent bar 132, as will be apparent from a reference to Figs. 3 and 8, may also form the means for operatively connecting the studs 91, to the plate 21a, the studs being threaded into bores in the bar 132.

Carried on the panel 131 is an upper limit switch 135T, an intermediate or neutral switch 135N, and a lower or bottom limit switch 135B. Also carried by the panel 131 is a pair of operating switches 136 and 137, the former being associated with the operating lever 8 and the latter with the cap member 9, whereby the switches may be operated by their respective associated members. In the embodiment of the invention illustrated, the switches 136 and 137 are mounted on hori-

zontally extending brackets 138 and 139, respectively, carried by the panel 131. The switches 135T, 135N and 135B are provided with operating levers 141T, 141N and 141B, respectively, each of which is provided at its free end with a roller 142. Cooperable with such rollers 142, as illustrated in Figs. 4 and 8, is an extension member 143 threaded on the end 126 of the pin 124, a lock washer or other suitable means 144 being interposed between the extension 143 and the nut 129, if desired. The free end of the extension 143 may terminate in a cylindrical portion 145 which is adapted to engage the rollers 142 as the piston rod 53 is reciprocated, with the limit switches being operative to control the hydraulic cylinder, and thus the reciprocation of the crimping mechanism 5.

Electrical control circuits

Fig. 13 illustrates in diagrammatic form a suitable electric control system for the mechanism heretofore described. Each of the switches 135T, N and B comprises two pairs of cooperable contacts, one pair being designated NC and of normally closed construction, while the other pair is designated NO and of normally open construction, so that when the particular actuating lever 141 associated with any one of the switches is operatively engaged by the extension member 143, the contacts NC of such switch will be open and the contact NO closed, or in other words, the positions will be reversed to that illustrated in Fig. 13.

The construction of the switch 135N and switch arm 141N is such that the switch is actuated only on upward movement of the actuating arm 141N and is inoperative when the arm is moved downwardly as the piston rod 53 moves downward.

Associated with each limit switch is a corresponding operating relay, the relay associated with the switch 135T being designated as TR, indicating the top operating relay, the switch 135N with the relay NR and the switch 135B with the relay BR. Each of the relays includes two pairs of normally open contacts and a relay winding, one pair of contacts of each relay being designated LI and being operative, as hereinafter described, to lock in the particular relay when the relay is initially actuated. The other pair of contacts of each relay is designated U or D, as the case may be, indicating that those particular contacts involve the actuation of the directional valve 17 to move the piston either up or down.

The motor 16 is diagrammatically illustrated in Fig. 13 as being of a three phase type and adapted to be operatively connected to a three phase line L through a suitable fused switch box indicated generally by the numeral 146, with lines y and x of the line L being utilized for operation of the relays and valve 17.

As illustrated, one side of both the "down" and "up" circuits for the valve 17 may be operatively connected to the line y as may be one side of each of the relay windings. The opposite side of the down circuit of the valve 17 is operatively connected to one of the contacts D of the relay TR, the other cooperable contact of the relay being operatively connected to the line x of the power line, so that when the relay TR is actuated the valve 17 will be actuated to a position to permit downward movement of the piston and piston rod 53 of the cylinder 13. In similar manner one contact of the contacts U of the relay NR and one of the contacts U of the relay BR may be connected in parallel to the other side of the up circuit of the valve 17, the other contact of each pair being operatively connected to the line x, so that when either of the relays NR or BR is actuated, the valve 17 will be actuated to permit upward movement of the piston rod 53.

One contact of the contact LI of the relay TR may be connected to the opposite winding of the relay and through the contacts NO of the switch 135T to the line x, while the other contact LI of the relay may be operatively connected to the line x through the normally closed contacts

NC of the switch 135B. In similar manner, one contact of the contact LI of the relay NR may be connected to the corresponding end of the associated relay winding and to the line x through normally open contact NO of the switch 135N, normally open contacts of the switch 137 and normally open contacts of the switch 136, all of which are in series with the relay winding and the line x. The other contact of the contact LI of the relay NR may be connected to the line through normally closed contacts NC of the switch 135T. Provision is also made for manually actuating the relay NR independently of the switches 135 by a manually operable switch 147 which connects the winding of the relay NR to the line x, thereby actuating the same. The contacts LI of the relay 15 BR are also connected in a similar manner, one contact being connected to the winding of the relay and also to the line x through the normally open contacts NO of the switch 135B, while the other contact of the contacts LI is operatively connected to the line x through normally 20 closed contacts NC of the switch 135N.

Operation

The general operation of the machine may be visualized from a reference to Figs. 3, 4, 6, 8 and 10, Figs. 4, 6 and 8 illustrating different positions of the crimping mechanism and the seal therein.

The master switch 146 is initially closed to actuate the motor 16 and pump 15, the latter being provided with a suitable by-pass for the flow of oil when the cylinder 13 is not actuated. Assuming there is no seal in the jaws 32 as illustrated in Fig. 6, the operator may close the switch 147, to actuate the relay NR, closure of the lock-in contacts LI of which will lock the winding to the line x to maintain the relay NR actuated. Actuation of the latter will also result in closing of the contacts U thereof to actuate the valve 17 for upward movement of the piston rod 53 and crimping mechanism, which will continue to move upward until the portion 145 of the extension 143 carried by the pin 124 engages and actuates the switch arm 141T of the top switch 135T, resulting in actuation of such switch to close the contacts NO thereof and open the contacts NC thereof.

Opening of the latter contacts will thereby break the lock-in circuit to the relay NR, permitting the latter to fall, while closing of the contacts NO of the switch 135T will result in actuation of the relay TR, the latter being locked on the line x through the contacts LI of the relay in series with the contacts NC of the switch 135B, and upon closing of the contacts D of the relay TR the valve 17 will be actuated to permit the piston to be moved downwardly, past the switch arm 141N, which will not actuate the switch 135N which action will continue until the extension 143 operatively engages the switch arm 141B of the switch 135B to actuate the latter, opening the contacts NC thereof to permit the relay TR to fall, and closing the contacts NO thereof to actuate the relay BR. Upon such actuation the contacts LI thereof will be closed, locking the relay to the line x through the normally closed contacts NC of the switch 135N, and at the same time closing the contacts U of the relay BR to reverse the valve 17, causing the piston to move upwardly.

The piston rod 53 and crimping mechanism will move upwardly until the extension 143 engages the arm 141N to actuate the switch 135N, opening the winding of the relay BR and permitting the latter to fall. Upon such actuation the piston and piston rod, as well as the crimping mechanism carried thereby, will stop its upward movement as the closing of the contacts NO of the switch 135N will be inoperative to continue movement of the crimping mechanism until the switches 136 and 137 have been simultaneously closed to close the circuit to the relay NR. Consequently the crimping mechanism 70 will stop at the neutral position defined by the switch

135N. However, upon closing of the switches 136 and 137, the complete cycle will be repeated, the mechanism moving upward until the switch 135T is actuated, then downwardly until the switch 135B is actuated, and upwardly to the neutral position when switch 135N is actuated.

During the cycle of operation the crimping and feeding mechanism will complete a cycle as follows: The actuating arm 141N of the switch 135N is so adjusted with respect to the extension 143 that actuation of the switch will take place when the piston rod 53 has moved upwardly to bring the elements of the crimping mechanism into the position illustrated in Fig. 6. In this position a single seal 64 will be supported on the horizontally extending portions 148 of the jaws 32, the portions 149 of the jaws engaging the side walls 66 of the seal adjacent the upper edges thereof, as clearly shown in Fig. 6, with the jaws being slightly closed to exert pressure on the seal and thus hold it in place in the sealing mechanism. Referring to Fig. 6 it will be noted that when the mechanism is in such position the rollers 48 have moved to a position to pass above the ends of the guide rails 49 and at the same time have urged the lower cutter 37 and plate 38 upwardly, whereby the pins 31 are positioned in the bottom of the slot 39 of the respective members.

The crimping jaws will thus be in an open position, holding a seal therein ready for the insertion of the strap ends to be joined together, and upon the insertion of the strap ends in position directly above the seal, which would normally position the hands of the operator to permit them to readily depress the lever 8 and cap 9 to actuate the switches 136 and 137, the piston rod 53 will move upwardly until the extension 143 engages and actuates the arm 141T of the switch 135T. During such upward movement the links 46 will rotate the jaws 32 into the position illustrated in Fig. 8, resulting in a shearing and deformation of the edges of the seals adjacent the punch blocks 33, as clearly illustrated in Fig. 8, and at the same time the rollers 48 will have disengaged from the members 37 and 38, which are free to move downwardly out of the way of the jaws and punch block. The arm 141T is so adjusted with relation to the switching mechanism and the extension 143 that actuation of the switch 135T will take place when the mechanism reaches the position illustrated in Fig. 8, thereby reversing the movement of the piston rod 53 and crimping mechanism 5, the first action being the engagement of the rollers 48 with the top edge 50 of the guide rails 49, followed by engagement of the rollers with the adjacent portion of the respective members 37 and 38, whereby continued movement of the piston rod will result in the rollers 48 camming the members 37 and 38 upwardly, having the effect of pushing the crimped seal and straps off of the punch blocks 33 and out of the crimping mechanism.

As the rollers 48 ride off of the top edges of the guide rails 49 the entire crimping mechanism may move downwardly, the various members approximating the positions illustrated in Fig. 4, and as the members 37, 38 and portions 35 of the punch blocks 33 pass below the lower edge of slot 27 which as previously noted defines the bottom of the passageway 63, the rollers 122 will engage the inclined surfaces 121 of the cam blocks 119, urging the latter to the left as viewed in Fig. 3, resulting in axial movement of the shafts 105 in the same direction, which is operative to rock the lever 84 in a clockwise direction as viewed in Fig. 3, resulting in a feeding movement of the pawl 94 to advance the strip of seals the length of a single seal, the pins 99 engaging the rear edge 71 of the second seal from the leading end and the leading edge 71 of the third seal, to accurately position the leading seal above the crimping mechanism. Upon consummation of such advancing movement under the action of the rollers 123, the extension 143 will engage the actuating arm 141B of the switch 135B, the arm being suit-

ably adjusted to achieve the desired results, thereby reversing the direction of movement of the piston rod 53 and the latter and associated crimping mechanism will thereupon begin to move upwardly. Simultaneously therewith as the rollers 122 begin disengagement from the cam blocks 119, the lever 84 will return to its original position as illustrated in Fig. 3, under action of the spring 111, the pins 99 retaining the strip of seals in advanced position, while the pawl 94 rotates downwardly out of engagement with the slots 68 and rides along the bottom wall 65 of the seal until it moves upwardly under action of the spring 96, when the lugs 98 on the pawl reach the juncture of the two seals immediately behind the pins 99.

15. As the mechanism continues to move upwardly, upon the cutting edge of the lower cutter block 37 reaching the connected seal, such cutter will cooperate with the upper block 58 to shear the leading seal from the strip, Fig. 4 illustrating the parts as the lower cutter approaches engagement with the seal.

20. To prevent springing movement, etc. of the seal as it is severed from the strip and thus possibly movement out of the desired position for further operations thereon, suitable means may be provided for preventing upward movement of the seal from the crimping mechanism at the time of severance, such means in the embodiment illustrated comprising a hold-down arm 150 pivotally supported on a pin 150' carried by an upright or standard 25. 151 mounted on the plate 3, the arm 150 being biased in a counterclockwise direction as viewed in Fig. 4 by a torsion spring 152. As illustrated, the arm 150 is more or less C-shaped to provide clearance for the adjacent jaw 33 and is provided with a generally rectangular shaped portion 153, which may have rounded edges, engageable 30. with the seal to initially hold the seal in place. As will be apparent from a reference to Figs. 6 and 8, as the crimping mechanism continues to move upwardly following shearing of the seal, the adjacent jaws 33 will engage the corner 154 of the arm 150, camming the arm upwardly out of engagement with the seal and providing free access to the seal, with the strap ends to be joined after the mechanism has reached the position illustrated in Fig. 6, following which the structure is ready for another sealing cycle.

35. 45. It will be noted that the crimping and advancing mechanism all may be mounted on the plate 3 which may be readily removed as a unit from the cabinet structure, the top of which may be provided with an opening underneath the plate 3 of a size to permit passage of the mechanism therethrough, with the exception of the panel 131 and associated structure which may be dismounted prior to the removal of the mechanism from the cabinet. Thus maintenance problems are facilitated as one mechanism may be readily substituted for another with relatively minor, substantially quickly performed operations.

50. 55. It will be noted that as the side walls 66 of the seal are in initially open position at the time the strap ends are inserted therein, the mechanism will readily fold over such side walls and effectively crimp the seal, even though the width or thicknesses of the straps may vary somewhat, the action of the jaws tightly folding and wrapping the seal over upon the adjacent band ends, followed by the crimping of the seals. It will be apparent from the above description that we have provided a novel crimping mechanism in conjunction with novel advancing means

60. 65. for seals in strip form, which construction is relatively simple in operation, very rugged and dependable and yet may be readily adjusted to insure satisfactory efficient operation.

70. 75. Having thus described our invention, it is obvious that various immaterial modifications may be made in the same without departing from the spirit of our invention; hence we do not wish to be understood as limiting ourselves to the exact form, construction, arrangement and combination of parts herein shown and described, or uses mentioned.

What we claim as new and desire to secure by Letters Patent is:

1. In a sealing device for joining a pair of strap ends, the combination of a seal deforming mechanism comprising a base plate, having an opening therein, a pair of spaced parallel side plates associated with said base plate and extending through said opening therein, each having a pair of longitudinally extending parallel slots therein, the slots in one plate being laterally aligned with the corresponding slots in the other plate, a pair of parallel pins extending between said plates with opposite ends positioned in aligned slots, a plurality of spaced crimping jaws carried by each pin, punchblocks interposed between adjacent jaws, a pair of members interposed between said jaws and the respective side plates, one of said members having a cutting edge thereon, said pins extending through said punchblocks and through slots in said members extending parallel to the slots in said side plates whereby said members may move relative to said pins, a reciprocable member positioned between said plates with its axis of movement extending parallel to the slots in said plates, a plurality of links, each pivotally connected at one corresponding end to said reciprocable member, certain of said links being connected by a pin to the jaws carried by one of the first mentioned pins and the other links being connected by another pin to the jaws carried by the other of said first-mentioned pins, said link connecting pins each extending parallel to the associated jaw carrying pin and having rollers at each end positioned adjacent the respective side plate, guide rails associated with the respective side plates cooperable with said rollers to control the pivotal action of said jaws about their axes whereby said jaws may move into seal-crimping positions when said rollers pass beyond the outer ends of said rails, said slotted members having means thereon engageable with said rollers operative to move said members toward the free ends of said jaws, during return movement of said mechanism following the crimping of a seal, for disengaging the same and straps connected thereby, from the punch blocks, the side plate adjacent said cutter member having a slot therein extending transverse to the parallel slots therein, a cutter block mounted in said transverse slot, cooperable with said base plate to form a passageway therebetween for a seal, and cooperable with said cutter member when said sealing mechanism is reciprocated, to shear a seal from a strip extending from said passageway, a pair of seal guides and a removable cover member cooperable with said base plate to guide seals through said passageway into said mechanism, a lever pivotally carried by said base plate on an axis positioned below the latter, a seal engaging pawl pivotally carried by said lever, spring means urging said pawl in a seal engaging direction, cooperable means on said lever and reciprocating member for transmitting movement of the latter to said lever in a seal feeding direction as the member approaches the end of its movement in a direction away from the free ends of said side-plates, spring means operative to urge said lever in a return direction, a hydraulic cylinder having a piston operatively connected to said reciprocable member, electro-magnetic valve means for controlling the flow of fluid to said cylinder, switch means for reversing the flow of fluid to said cylinder at opposite ends of the travel of said reciprocable member and for stopping the latter prior to seal crimping movement of said jaws to permit engagement of the strap ends to be joined with a seal positioned in said jaws, means carried by said reciprocable member cooperable with said switch means for operatively actuating the latter, and manually actuatable switch means for actuating said valve means to initiate movement of said mechanism toward the seal crimping position thereof.

2. In a band sealing device, the combination of a seal deforming mechanism comprising a base plate, having

an opening therein, a pair of spaced parallel side plates associated with said base plate and extending through said opening therein, each having a pair of longitudinally extending parallel slots therein, the slots in one plate being laterally aligned with the corresponding slots in the other plate, a pair of parallel pins extending between said plates with opposite ends positioned in aligned slots, a plurality of spaced crimping jaws carried by each pin, punchblocks interposed between adjacent jaws, a pair of members interposed between said jaws and the respective side plates, one of said members having a cutting edge thereon, said pins extending through said punchblocks and through slots in said members extending parallel to the slots in said side plates whereby said members may move relative to said pins, a reciprocable member positioned between said plates with its axis of movement extending parallel to the slots in said side plates, a plurality of links, each pivotally connected at one corresponding end to said reciprocable member, certain of said links being connected by a pin to the jaws carried by one of the first mentioned pins and the other links being connected by another pin to the jaws carried by the other of said first-mentioned pins, said link connecting pins each extending parallel to the associated jaw carrying pin and having rollers at each end positioned adjacent the respective side plate, and guide rails associated with the respective side plates cooperable with said rollers to control the pivotal action of said jaws about their axes whereby said jaws may move into seal-crimping positions when said rollers pass beyond the outer ends of said rails, said slotted members having means thereon engageable with said rollers operative to move said members toward the free ends of said jaws, during return movement of said mechanism following the crimping of a seal, for disengaging the same and straps connected thereby, from the punch blocks.

3. In a band sealing device, the combination of a seal deforming mechanism comprising a base plate, having an opening therein, a pair of spaced parallel side plates associated with said base plate and extending through said opening therein, each having a pair of longitudinally extending parallel slots therein, the slots in one plate being laterally aligned with the corresponding slots in the other plate, a pair of parallel pins extending between said plates with opposite ends positioned in aligned slots, a plurality of spaced crimping jaws carried by each pin, punchblocks interposed between adjacent jaws, a pair of members interposed between said jaws and the respective side plates, one of said members having a cutting edge thereon, said pins extending through said punchblocks and through slots in said members extending parallel to the slots in said side plates whereby said members may move relative to said pins, a reciprocable member positioned between said plates with its axis of movement extending parallel to the slots in said side plates, a plurality of links, each pivotally connected at one corresponding end to said reciprocable member, certain of said links being connected by a pin to the jaws carried by one of the first mentioned pins and the other links being connected by another pin to the jaws carried by the other of said first-mentioned pins, said link connecting pins each extending parallel to the associated jaw carrying pin and having rollers at each end positioned adjacent the respective side plates, guide rails associated with the respective side plates cooperable with said rollers to control the pivotal action of said jaws about their axes whereby said jaws may move into seal-crimping positions when said rollers pass beyond the outer ends of said rails, said slotted members having means thereon engageable with said rollers operative to move said members toward the free ends of said jaws, during return movement of said mechanism following the crimping of a seal, for disengaging the same and straps connected thereby, from the punch blocks, the side plate adjacent said cutter member having a slot

therein extending transverse to the parallel slots therein, and a cutter block mounted in said transverse slot, cooperable with said base plate to form a passageway therebetween for a seal, and cooperable with said cutter member when said sealing mechanism is reciprocated, to shear a seal from a strip extending from said passageway.

4. In a band sealing device, the combination of a seal deforming mechanism comprising a base plate, having an opening therein, a pair of spaced parallel side plates associated with said base plate and extending through said opening therein, each having a pair of longitudinally extending parallel slots therein, the slots in one plate being laterally aligned with the corresponding slots in the other plate, a pair of parallel pins extending between said plates with opposite ends position in aligned slots, a plurality of spaced crimping jaws carried by each pin, punchblocks interposed between adjacent jaws, a pair of members interposed between said jaws and the respective side plates, one of said members having a cutting edge thereon, said pins extending through said punchblocks and through slots in said members extending parallel to the slots in said side plates whereby said members may move relative to said pins, a reciprocable member positioned between said plates with its axis of movement extending parallel to the slots in said side plates, a plurality of links, each pivotally connected at one corresponding end to said reciprocable member, certain of said links being connected by a pin to the jaws carried by one of the first mentioned pins and the other links being connected by another pin to the jaws carried by the other of said first-mentioned pins, said link connecting pins each extending parallel to the associated jaw carrying pin and having rollers at each end positioned adjacent the respective side plates, guide rails associated with the respective side plates cooperable with said rollers to control the pivotal action of said jaws about their axes whereby said jaws may move into seal-crimping positions when said rollers pass beyond the outer ends of said rails, said slotted members having means thereon engageable with said rollers operative to move said members toward the free ends of said jaws, during return movement of said mechanism following the crimping of a seal, for disengaging the same and straps connected thereby, from the punch blocks, the side plate adjacent said cutter member having a slot therein extending transverse to the parallel slots therein, a cutter block mounted in said transverse slot, cooperable with said base plate to form a passageway therebetween for a seal, and cooperable with said cutter member when said sealing mechanism is reciprocated, to shear a seal from a strip extending from said passageway, a pair of seal guides and a removable cover member cooperable with said base plate to guide seals through said passageway into said mechanism, a lever pivotally carried by said base plate on an axis positioned below the latter, a seal engaging pawl pivotally carried by said lever, spring means urging said pawl in a seal engaging direction, cooperable means on said lever and reciprocating member for transmitting movement of the latter to said lever in a seal feeding direction as the member approaches the end of its movement in a direction away from the free ends of said side-plates, and spring means operative to urge said lever in a return direction.

5. In a band sealing device, the combination of a seal deforming mechanism, a reciprocable member operatively connected to said deforming mechanism for actuating the latter, a seal guide operative to guide seals into said mechanism, means for advancing the leading seal of strips of connected seals into said mechanism, a pair of spring biased index pins extending inwardly from said seal guide, adapted to engage said strip of seals intermediate two adjacent seals to accurately position the leading seal thereof following advance of the strip, in said deforming mechanism, means for severing the leading seal from the strips subsequent to its insertion into said mechanism, and

means for operatively actuating said advancing means, said severing means, and said deforming mechanism.

6. In a band sealing device, the combination of a seal deforming mechanism, a reciprocable member operatively connected to said deforming mechanism for actuating the latter, a hydraulic cylinder having a piston operatively connected to said reciprocable member, electro-magnetic valve means for controlling the flow of fluid to said cylinder, switch means for reversing the flow of fluid to said cylinder at opposite ends of the travel of said reciprocable member and for stopping the latter prior to seal deforming movement of said mechanism to permit engagement of the strap ends to be joined with a seal positioned in said mechanism, means carried by said reciprocable member cooperable with said switch means for operatively actuating the latter, and switch means for actuating said valve means to initiate movement of said mechanism toward the seal deforming position thereof.

7. In a band sealing device, the combination of a base plate having an opening therein, a seal deforming mechanism extending through said opening, a reciprocable member operatively connected to said deforming mechanism for actuating the latter, a pair of seal guides and a removable cover member cooperable with said base plate to guide seals from a seal supply into said mechanism, a lever pivotally carried by said base plate on an axis positioned below the latter, a seal engaging pawl pivotally carried by said lever, spring means urging said pawl in a seal engaging direction, cooperable means on said lever and reciprocating member for transmitting movement of the latter to said lever in a seal feeding direction as the member approaches the end of its movement in a retroacting direction, spring means operative to urge said lever in a return direction, and a pair of spring biased index pins extending inwardly from said seal guides adapted to engage a seal to accurately position the leading seal, following advance of the strip, in said deforming mechanism.

8. In a sealing device for joining a pair of strap ends, the combination of a seal deforming mechanism movable from an inoperative position to a seal deforming position, a reciprocable member operatively connected to said deforming mechanism for actuating the latter, means for feeding seals into said mechanism, actuating reversible means operatively connected to said reciprocable member, control means for reversing said actuating means at opposite ends of the travel of said reciprocating member and for stopping the latter prior to seal deforming movement of said mechanism to permit engagement of the strap ends to be joined with a seal positioned in said mechanism, means carried by said reciprocable member cooperable with said control, means for operatively actuating the latter, and means for initiating movement of said mechanism toward the seal deforming position thereof.

9. In a band sealing device, the combination of a base plate having an opening therein, a seal deforming mechanism extending through said opening, a reciprocable member operatively connected to said deforming mechanism for actuating the latter, a pair of seal guides and a removable cover member cooperable with said base plate to guide seals into said mechanism, a lever pivotally carried by said base plate on an axis positioned below the latter, a seal engaging pawl pivotally carried by said lever, spring means urging said pawl in a seal engaging direction, cooperable means on said lever and reciprocating member for transmitting movement of the latter to said lever in a seal feeding direction as the member approaches the end of its movement in a retroacting direction, and spring means operative to urge said lever in a return direction.

10. In a sealing device for joining a pair of strap ends, the combination of a base plate having an opening therein, a seal deforming mechanism extending through said opening, a reciprocable member operatively connected to said deforming mechanism for actuating the latter, a pair of

seal guides and a removable cover member cooperable with said base plate to guide successive seals connected together to form a strip into said mechanism, a lever pivotally carried by said base plate on an axis positioned below the latter, a seal engaging pawl pivotally carried by said lever, spring means urging said pawl in a seal engaging direction, cooperable means on said lever and reciprocating member for transmitting movement of the latter to said lever in a seal feeding direction as the member approaches the end of its movement in a retroacting direction, spring means operative to urge said lever in a return direction, a pair of spring biased index pins extending inwardly from said seal guides adapted to engage said strip of seals intermediate two adjacent seals to accurately position the leading seal thereof following advance of the strip, in said deforming mechanism, a hydraulic cylinder having a piston operatively connected to said reciprocable member, electro-magnetic valve means for controlling the flow of fluid to said cylinder, switch means for reversing the flow of fluid to said cylinder at opposite ends of the travel of said reciprocable member and for stopping the latter prior to seal deforming movement of said mechanism to permit engagement of the strap ends to be joined with a seal positioned in said mechanism, means carried by said reciprocable member cooperable with said switch means for operatively actuating the latter, and switch means for actuating said valve means to initiate movement of said mechanism toward the seal deforming position thereof.

11. In a power actuated band sealing device, the combination of a reciprocable sealing mechanism, power means for actuating said mechanism, means for feeding a seal into said mechanism, independently operable means at opposite sides of said sealing mechanism for controlling said actuating means to crimp a seal therein, and additional means for controlling said actuating means to reciprocate the mechanism when desired.

12. In a power actuated band sealing device, the combination of a seal crimping mechanism, power means for actuating said mechanism, and independently operable manually actuatable control means at opposite sides of said sealing mechanism for controlling said actuating means, and arranged to require the means at each side to be simultaneously manually actuated before said sealing mechanism is operative, to crimp a seal therein, and means for automatically feeding a seal into said mechanism subsequent to the crimping of a preceding seal.

13. In a power actuated band sealing device, the combination of a seal crimping mechanism, power means for actuating said mechanism, and independently operable

5 manually actuatable control means at opposite sides of said sealing mechanism for controlling said power means, and arranged to require the means at each side to be simultaneously actuated before said sealing mechanism is operated.

14. In a band sealing device, the combination of a sealing mechanism including a pair of crimping jaws adapted to crimp a seal on a pair of band ends, said mechanism being reciprocable along an axis, means for effecting partial closing of said jaws to support a seal therein when the sealing mechanism is in a first predetermined position on said axis, means for feeding a seal from a supply thereof to said mechanism when the latter is in a second predetermined position on said axis, automatic 10 means for controlling the reciprocation of said sealing mechanism from the first predetermined position to the second predetermined position, and its return to the first predetermined position, and means for controlling the seal crimping movement of said jaws when the mechanism is in said first predetermined position.

15. In a band sealing device, the combination of a sealing mechanism adapted to crimp a seal on a pair of aligned band ends, and including seal deforming means and a cooperable pair of clamping jaws, said deforming 25 means and jaws being reciprocable along an axis transverse to the axis of said pair of band ends and said jaws being supported for movement relative to said deforming means for crimping a seal positioned on the latter, when the sealing mechanism is in a predetermined position relative to said strap axis, means for feeding a strip of connected seals relative to said mechanism when the latter is in another predetermined position relative to said strap axis, to position the leading seal of the strip in operative position in the sealing mechanism, means for severing such seal from said strip when said sealing mechanism is moved from its position during seal feeding to an intermediate position, automatic means for controlling the reciprocation of said sealing mechanism from seal crimping position to seal feeding position, and its return to the intermediate position, and manually actuatable means for controlling the movement of said jaws into the seal crimping position from said intermediate position.
